(57) **CLAIM**

The ornamental design for remote control, as shown and described.

DESCRIPTION

FIG. 1 is a perspective of a remote control in accordance with the present invention.

FIG. 2 is a front elevational view of the remote control of the present invention.

FIG. 3 is a rear elevational view of the remote control of the present invention.

FIG. 4 is a left-hand elevational view of the remote control of the present invention.

FIG. 5 is a right-hand elevational view of the remote control of the present invention.

FIG. 6 is a top view of the remote control of the present invention.

FIG. 7 is a bottom view of the remote control of the present invention.

FIG. 8 is a perspective of a second embodiment of the remote control of FIG. 1; and,

FIG. 9 is a front elevational view in accordance with the second embodiment thereof, of the remote control of FIG. 1, with the second embodiment having a rear elevational view, a left hand elevational view, a right hand elevational view, a top view, and a bottom view that correspond, respectively, to FIGS. 3, 4, 5, 6 and 7.
